TORCH

Arthur A. Karcher and Clarence E. Brown,
Fostoria, Ohio, assignors to Barrett F. Brown,
Fostoria, Ohio

Application October 30, 1935, Serial No. 47,372

10 Claims. (Cl. 67—55)

This invention relates to devices for burning liquid fuel, and it relates more particularly to what are ordinarily called "torches", such as those used on highways, buildings, excavations and other places, for various purposes.

Generally stated, the object of the invention is to provide a novel and improved construction and arrangement whereby a torch of this kind is provided, which is practical and economical to manufacture, and which in use is better protected against rain and wind, in order to insure against blowing out of the flame, and which is constructed in a manner to insure better combustion, thereby to increase the effectiveness and visibility of the flame, under all conditions of weather.

It is also an object to provide certain details and features of construction and combinations tending to increase the general efficiency and the desirability of a torch of this particular character.

To the foregoing and other useful ends, the invention consists in matters hereinafter set forth and claimed and shown in the accompanying drawing, in which—

Fig. 1 is a plan view of a torch embodying the principles of the invention.

Fig. 2 is a side elevation of said torch.

Fig. 3 is a vertical section on line 3—3 in Fig. 1, on a larger scale.

Fig. 4 is a perspective of one of the elements of said torch.

Fig. 5 is a similar view of another element.

As thus illustrated, the invention comprises a hollow body 1, preferably of metal, provided at its top with an opening having an annular depending portion 2, provided at its lower end with an inturned horizontal flange 3, forming a seat for a packing ring 4 resting thereon. The top of said body is also provided with spring clips 5 for a purpose hereinafter explained.

The removable burner comprises the wick tube 6, formed with an external shoulder 7, and with an enlarged bottom portion 8, the lower edge of which latter rests upon the packing ring 4, previously mentioned. This tube 6 is adapted to hold the wick 9, which is made of any suitable material. The shell 10 is composed of a plurality of uprights providing spaces between them, with their lower ends united by the base portion 11, which latter rests on the shoulder 7, previously mentioned. An annular outer ring, having a straight vertical portion 12, and a lower outwardly flared portion 13, the latter forming a beveled flange, is secured to the shell 10 in posi-

tion to protect the flame against wind, and to admit air below it through the spaces between the lower ends of the uprights of which the shell 10 is composed. The upper ring is composed of a straight upper portion 14, having an upper inturned flange 15, provided with openings 16 to receive the reduced upper end portions 17 of said uprights, forming a top opening 18 for the flame, and this ring also has a bottom flange 19 that is downwardly flared, thereby to admit air between the lower edge of this flange and the upper edge of the portion 12 to the flame, and providing enough space between the two flange rings to permit lighting of the wick. The top plate 20 is preferably a metal disk provided with openings 21 to receive the upper end portions 22 of the shell 10, which upper end portions may be bent down to fasten the plate in place. This plate 20 forms a cap or top piece for the burner and is provided with tongues 23, struck up from the middle of the plate, as shown, thus forming openings 24 in the top wall of the cap, with the plate 20 spaced a distance above the upper edge of the upper flange ring 14, previously mentioned.

The burner thus constructed is preferably provided with radial arms 25 for engagement with the under sides of the spring clips 5, previously mentioned, thereby to tightly hold the burner in place within the socket formed by the portion 2, previously mentioned, and upon the packing ring 4, previously mentioned, thus forming a tight joint which will prevent leakage of the fuel, whereby the latter can only escape by capillary attraction, as well as by internal pressure, through the wick to the flame.

With the burner thus constructed, there will always be an air space above the liquid fuel, inasmuch as the level of the latter will be approximately in the plane of the flange 3, and this pocketing of the air in the top of the hollow body tends to prevent overheating of the fuel and prevents the latter from escaping and flowing over the top of the hollow body, where it would ignite and might form a serious fire hazard. The beveled flange rings 12 and 14 have a tendency to divert all winds and rain from the interior of the burner, as also do the tongue openings 24 in the cap at the top of the burner. At the same time, these tongue openings tend to cause the burning gases to converge upwardly, with air, to provide an effective light. In other words, the construction not only more effectively protects the flame against wind and rain, but also tends to insure better combustion of the

fuel, thereby providing a practically non-blow-out flame of better visibility. And, as shown and described, the burner is tightly held in a depression in the top of the hollow body which contains the fuel, preventing leakage of the latter, while at the same time making it easy to remove and insert the burner.

The ring 11, with its integral upstanding portions 10, is an important feature of the invention, 10 it will be seen, inasmuch as with this feature the construction is not only strong and effective in use, but is also comparatively simple and characterized by a comparatively low cost of production, as practically only sheet metal is used, and the stamping and forming operations are simple 15 and comparatively inexpensive.

The construction thus provided results, it will be seen, in the provision of a cage-like housing for protecting the flame against rain and wind, 20 the entire housing being supported by means having a tight fit on the wick tube. This construction is comparatively inexpensive, but at the same time very effective in use.

What we claim as our invention is:

- 25 1. In a torch, a hollow body for the fuel, having a countersink or recess in the top thereof, a wick tube expanded at its lower end to rest in said recess, a ring encircling the reduced upper end portion of the wick tube, with a shoulder 30 formed on the tube to support the ring, integral upright portions on the outer edge of said ring, a top plate fastened to the upper ends of said upright portions, the latter being spaced apart to provide air inlets between them, and a plurality 35 of rings encircling said upright portions, spaced one above the other, and provided with outwardly flared lower edge portions, forming an apertured enclosure for the flame to protect the latter against wind and rain.
- 40 2. A structure as specified in claim 1, said top plate being apertured and formed of integral inclined portions overhanging the apertures.
- 45 3. A structure as specified in claim 1, the ring immediately below said top plate having its upper edge flanged inwardly, with notches in the flange to embrace the upper end portions of said upright portions.
4. A structure as specified in claim 1, said recess having an inwardly extending bottom flange.

and said wick tube having its lower end supported on said flange, together with means for tightly holding the wick tube in place on the seat formed by said flange.

5. In a torch, a hollow body for the fuel, with an opening in the top thereof, a wick tube removably connected to said opening, a ring encircling and fastened on said tube, said ring having a plurality of integrally formed upright portions spaced apart at the annular outer edge 10 thereof, forming air inlet openings between said upright portions, a plurality of annular members encircling and fastened to said upright portions, one above the other, with space between them, providing a plurality of upwardly converging bevelled flanges overhanging said openings, so that air may enter upwardly under each bevelled flange, with means forming an apertured covering above the top of the interior of the cage-like housing thus formed around the upper end of 20 the wick, to protect the flame against rain and wind.

6. A structure as specified in claim 5, in which each bevelled flange is integral at its upper edge with a cylindrical ring-like portion fastened to 25 said upright portions, with the inner surface of said ring-like portion exposed between said upright portions.

7. A structure as specified in claim 5, the lower and outer edge of one bevelled flange being substantially in the plane of said ring on the wick tube and below the plane of the upper end of 30 said tube.

8. A structure as specified in claim 5, said ring on the wick tube having its inner edge turned up 35 to provide a cylindrical upstanding portion that tightly embraces the wick tube.

9. A structure as specified in claim 5, said wick tube being expanded at its lower end and said ring having a tight fit on the tube immediately 40 above said expanded base portion thereof, with a shoulder on the tube above the base to support said ring.

10. A structure as specified in claim 5, the upper ends of said upright portions having direct seating engagement with said apertured covering. 45
